INVENTOR
J. C. Prewitt

by *Maurice L. Atty's.*

UNITED STATES PATENT OFFICE.

JOHN C. PREWITT, OF SANTA MARGARITA, CALIFORNIA.

ROAD-MAP HOLDER.

Application filed May 8, 1922. Serial No. 559,355.

To all whom it may concern:

Be it known that I, JOHN C. PREWITT, a citizen of the United States, and a resident of Santa Margarita, county of San Luis Obispo, and State of California, have invented a new and useful Road-Map Holder, of which the following is a specification.

The present invention relates to improvements in holders for maps and the like and the particular object of the invention is to provide a convenient means for drivers of motor vehicles to have a road map supported in front of them so as to be visible without any effort. It is proposed to provide a holder of the character described that may be secured to the dash-board or any other convenient place within view of the driver, and which allows a road map of convenient shape to be slipped in and out conveniently, the particular design allowing the map to be supported vertically or horizontally.

With these objects in view I have illustrated the preferred form of my invention in the accompanying drawing, in which Figure 1 shows a plan view of my map holder; Figure 2 a cross section through the same along line 2—2 of Figure 1, and Figure 3 a vertical cross section through the same along line 3—3 of Figure 1. While I have shown only the preferred form of the invention it should be understood that various changes or modifications may be made within the scope of the claims hereto attached without departing from the spirit of the invention.

My device consists of a backing (1) and a spring (2). The backing comprises a smooth piece of metal (3) being elongated in form and having two straight edges (4) and curved ends (6). The two straight edges (4) have flanges (7) rising therefrom in parallel relation. The latter, however, do extend through the whole length of the straight edges but only a short distance beyond half the length. In these two flanges are supported two pins (8) in axial relation and extending toward each other, each being provided with a head (9) at its inner end. The wire spring (2) consists pref-

erably of a single endless loop corresponding in form substantially to the outlines of the backing but being somewhat smaller. A central portion (11) of the loop is wound on the two pins (8) so as to cause a tension in the two ends (12) of the loop to press against the backing at opposite ends of the latter. For convenience in handling each end member of the loop is provided with a bent portion (14) allowing the finger of the operator to get a good hold of the end of the spring if he wishes to lift the same for the purpose of inserting the map.

The use of my device will be readily understood from the foregoing description. The map (15) which is substantially of the shape of a blotter and which is shown in dotted lines in Figure 1 may be inserted either lengthwise so as to cover substantially all the backing or transversely, making use of the fact that the two flanges (7) do not extend throughout the whole length of the edges. Suitable perforations (16) are provided in the backing for fastening the same to the dash-board of an automobile or in any other convenient place.

I claim:

1. A holder for maps and the like comprising a flat back having two parallel marginal flanges thereon, co-axial pins supported in the flanges extending toward each other and a wire spring having its central portion wound on the two pins with its ends pressing on the back for holding the map.

2. A holder for maps and the like comprising a flat back having two parallel marginal flanges thereon, co-axial pins supported in the flanges extending toward each other, and a wire spring forming a closed loop having its central portion wound on the two pins with its ends pressing on the back for holding the map.

3. A holder for maps and the like comprising a flat back having two parallel marginal flanges thereon, co-axial pins supported in the flanges extending toward each other, a wire spring forming a closed loop having its central portion wound on the two pins with its ends pressing on the back for holding the map and with a bend in

each end of the loop facilitating the manipulation of the same.

4. A holder for maps and the like comprising a flat back having two parallel edges

5 and marginal flanges rising therefrom, coaxial pins supported in the flanges extending toward each other and a wire spring

forming a closed loop having its central portion wound on the two pins with its ends pressing on the back for holding the 10 map, the flanges stopping short of the ends of the backing so as to allow the map to be held transversely as well as longitudinally.

JOHN C. PREWITT.
